UNITED STATES PATENT OFFICE.

HENRY TAYLOR KAY, OF TOPEKA, KANSAS, ASSIGNOR OF ONE-HALF TO
DAVID O. CRANE, OF SAME PLACE.

TIRE-TIGHTENER.

SPECIFICATION forming part of Letters Patent No. 636,204, dated October 31, 1899.

Application filed July 15, 1899. Serial No. 723,977. (No model.)

To all whom it may concern:

Be it known that I, HENRY TAYLOR KAY, a citizen of the United States, residing at Topeka, in the county of Shawnee and State of 5 Kansas, have invented a new and useful Tire-Tightener, of which the following is a specification.

The invention relates to improvements in tire-tighteners.

10 The object of the present invention is to improve the construction of tire-tighteners and to provide a simple, inexpensive, and efficient device adapted to be readily arranged for operating on the front and rear wheels of 15 a vehicle for forcing the felly outward to expand the same against the tire and capable of spreading the felly-sections to enable a washer or plate to be readily introduced between the same to retain the felly in its expanded condition.

20 The invention consists in the construction and novel combination and arrangement of parts hereinafter fully described, illustrated in the accompanying drawings, and pointed 25 out in the claims hereto appended.

In the drawings, Figure 1 is a longitudinal sectional view of a tire-tightener constructed in accordance with this invention and shown applied to a wheel. Fig. 2 is a perspective 30 view of the tire-tightener. Fig. 3 is a side elevation showing the tire-tightener arranged for expanding or spreading the felly-sections.

35 Like numerals of reference designate corresponding parts in all the figures of the drawings.

1 designates a tire-tightener comprising an inner section or bar 2, an outer section or block 3, and an intermediate section or block 4, which is connected by screws 5 and 6 with 40 the adjacent ends of the sections or members 2 and 3, and the said screws are adapted to be adjusted to vary the length of the device.

The bar or section 2 is provided at its inner end with an ear or lug 7, arranged at right angles to the same and provided with a threaded 45 perforation for the reception of the adjacent portion of the adjusting-screw 5, which has right and left hand threads, as clearly illustrated in Fig. 1 of the accompanying drawings, whereby when the screw is rotated the adjacent sections or members will be simul-

taneously moved in opposite directions to separate them or draw them together.

The adjusting-screw 5 is provided with a central polygonal portion 8, forming a wrench-seat and adapted to be engaged by an ordinary wrench.

The central or intermediate block or section 4 is provided at its ends with lugs or ears 9 and 10, extending outward at right angles 60 to the body portion of the block or section 4, arranged parallel with each other and having threaded perforations or openings for the reception of the adjacent portions of the adjusting-screws. 65

The outer section or member, which is substantially L-shaped, similar to the section or member 2, is provided at its inner end with a lug or ear 11, having a threaded opening for the outer portion of the adjusting-screw 70 6, which has right and left hand threaded portions similar to the adjusting-screw 5, and which is provided with a central polygonal portion forming a seat.

The bar or section 2 is adapted to bear 75 ranged against the hub of a wheel 12, as illustrated in Fig. 1 of the accompanying drawings, and the outer block or section 3 is fitted against the rim or felly and is adapted to expand the same, and a washer or ring may be 80 interposed between the shoulder of the spoke and the felly, as will be readily understood. The three sections or members are employed when the device is arranged as shown in Fig. 1, for operating on one of the hind wheels of 85 a vehicle; but when it is necessary to tighten the tire of the front wheel, which is of less diameter than the hind wheel, the sections 2 and 4 of the device are employed, the block or section 3 and the screw 6 being removed 90 to shorten the device and adapt it for small wheels.

The sections or members 3 and 4 may be separated from the bar or section 2 and are adapted to be arranged as illustrated in Fig. 95 3 of the accompanying drawings for spreading the felly-sections to enable washers or plates to be interposed between the same for retaining the felly-sections in their expanded condition. The sections or members 3 and 100 4 when employed for spreading the felly-sections are interposed between the adjacent

spokes and are arranged in the angles formed by the same and the felly-sections. The screw may then be adjusted to spread the felly-sections to the desired extent.

5 It will be seen that the tire-tightener is exceedingly simple and inexpensive in construction, that it is strong and durable, and that it may be readily adjusted and arranged for operating on the front and rear wheels of 10 a vehicle to expand the felly and to spread the sections of the same. It will also be apparent that the sections are removable, so that two or more of them may be operated together, and that when the outer section is 15 detached the device is adapted for front wheels and that when the inner section is removed the device may be arranged between the spokes.

Changes in the form, proportion, size, and 20 the minor details of construction within the scope of the appended claims may be resorted to without departing from the spirit or sacrificing any of the advantages of this invention.

What is claimed is—

25 1. A tire-tightener comprising an inner section or bar provided with a lug extending outward at right angles, an outer section or block provided at its inner end with a lug arranged parallel with the said lug, an intermediate 30 block or section provided at its ends with

parallel lugs interposed between the said lugs, and adjusting-screws engaging the lugs and detachably connecting the sections, substantially as described.

2. A tire-tightener comprising a substantially L-shaped section or member having a threaded opening in one of its arms, a section or member having a body portion and provided with a pair of parallel lugs having threaded openings and arranged parallel with the arm 40 having the threaded opening, and a screw connecting the sections or members and engaging the adjacent threaded openings, substantially as described.

3. A tire-tightener comprising the inner, 45 outer and intermediate sections provided at their adjacent ends with threaded openings, and the adjusting-screws connecting the sections and detachably engaging the threaded openings, whereby either the inner or outer 50 section and the screw for adjusting the same may be removed, substantially as and for the purpose described.

In testimony that I claim the foregoing as my own I have hereto affixed my signature in 55 the presence of two witnesses.

HENRY TAYLOR KAY.
